PRINTED TEXTILE FABRIC OR THE LIKE

Filed July 31, 1928

Inventor

Emile Ericson

By his Attorney

Emery Booth, Young, Nance

UNITED STATES PATENT OFFICE.

EMILE ERICSON, OF PELHAMWOOD, NEW YORK, ASSIGNOR TO NATIONAL FABRIC AND FINISHING COMPANY, OF NEW YORK, N. Y., A CORPORATION OF MASSACHUSETTS.

DESIGN FOR A PRINTED TEXTILE FABRIC OR THE LIKE.

Application filed July 31, 1928. Serial No. 27,645. Term of patent 3½ years.

To all whom it may concern:

Be it known that I, EMILE ERICSON, a citizen of the United States, residing at Pelhamwood, in the county of Westchester and State of New York, have invented a new, original, and ornamental Design for Printed Textile Fabrics or the like, of which the following is a specification, reference being had to the accompanying drawing, forming part thereof.

The single figure of the drawing is a plan view of a piece of printed textile fabric showing my new design.

Adjacent areas bounded by unbroken lines

are of contrasting colors or shades of the same color as indicated by like cross-hatching; and like cross-hatching represents like colors or shades of color.

The drawing shows a complete unit of the design which consists of sixteen blocks arranged in the relative position shown, which unit is repeated over the surface of the fabric.

I claim:

The ornamental design for a printed textile fabric or the like, as shown and described.

EMILE ERICSON.
